UNITED STATES PATENT OFFICE.

JAMES J. FITZGERALD, OF NEW YORK, N. Y.

AIR TURBINE.

Application filed October 8, 1924. Serial No. 742,281.

To all whom it may concern:

Be it known that I, JAMES J. FITZGERALD, a citizen of the United States, residing at New York city, in the county and State of New York, have invented certain new and useful Improvements in an Air Turbine, of which the following is a specification.

This invention relates to air turbines for heavier than air flying machines, and the objects of my improvement are to provide a construction of compact form and high power which will lift itself and the structure of which it is a part straight up into the air without traction or the necessity of running horizontally for any distance prior to leaving the surface of the earth.

This is accomplished by the use of a series of suction blades or vanes housed in a rotatable cylinder and secured at their peripheries to the wall of the said cylinder, with a second series of similar blades free at their peripheries from the cylinder wall, but attached to a central shaft which may be rotated in either direction.

In this structure the concentrated power of the compression which is governed by a valve like arrangement operated by the compression creates through the driving force of the induced air a lift of high power due to the direct thrust of the upwardly driven air.

Other advantages will appear in the following specification and drawings in which:

Fig. 1 is a plan view of a flying machine with my structure mounted thereon.

Fig. 2 is a side view of same.

Fig. 3 is a vertical sectional view of one of the cylinders showing two of the vanes in front elevation.

Fig. 4 is a sectional view taken on the line 4-4 of Fig. 3.

As shown in Figs. 1 and 2 the reference numeral 10 indicates the body of the machine on which are mounted the housings 11-11 for the cylinders 12, the latter having a gear 13 meshing with a driving gear 14 hooked to a motor of the usual type. Within the said cylinder 12 are two series of vanes or blades the first series 15-15 being secured at their peripheries to the wall of the cylinder 12, and free from attachment to the shaft 17 and the second series of vanes or blades 16-16 being rigidly attached to the shaft 17 and free of attach-

ment at their outer edges to the wall of 55 the cylinder 12.

As shown at 18 and 19 in Fig. 1 these vanes are formed with channels 20 running from the periphery to the hub, the openings at the periphery being curved and the 60 said curves running in reverse directions on the alternate vanes. It will also be noted that these channels are wider at their lower sections than at the top.

The shaft 17 is provided at its lower end 65 with a gear 21 which meshes with a driving gear 22 in turn connected with a motor of any usual type whereby the vanes 16 may be driven in the opposite direction to that in which the vanes 15 are rotated. At the upper end of the shaft 17 a spring 23 is mounted to permit its functioning as a valve the adjustment being such that the spring 70 will be operated by the compression force at a point below the pressure strength of 75 the walls of the cylinder 12.

The operation of the device is as follows:

The cylinder 12 is first rotated which 80 draws in air through the opening 24 at the upper end of the housing 11 and passes downwardly between the cylinder and the housing and into the cylinder where the compression begins immediately from the rotation of the vanes 15-15. When the compression reaches a certain determined point as indicated by a gauge (not shown), the vanes 16-16 are brought into operation 85 rotating in the opposite direction to that of the vanes 15-15 thereby increasing the compression and also causing a lift of marked 90 power.

To prevent the force of the compressed air from rending the wall of the cylinder 12, the spring 23 has only sufficient strength to 95 hold the shaft 17 in its closed position until the compression force reaches a point considerably less than the pressure strength of the said wall and consequently the shaft can be lifted by the pressure on the under side of the vanes 16-16 thereby permitting the air to escape through the opening 25 where it will again be inducted to the bottom of the cylinder.

Having thus described my invention, what 105 I claim is:

1. In an air turbine the combination of the following elements: a housing; a rotatable cylinder mounted therein; a shaft mounted

- in the said cylinder; a series of blades secured to the wall of the said cylinder and adapted to rotate around said shaft; a second series of blades mounted on the said shaft and adapted to rotate within the said cylinder and in the opposite direction to that in which the first series of blades is rotated; means adapted to rotate the said cylinder and first series of blades; means adapted to rotate the said shaft and the said second series of blades; and means adapted to permit the longitudinal movement of said shaft by compressed air.
2. In an air turbine the combination of the following elements; a housing, a rotatable cylinder mounted therein; means adapted to draw air into the said cylinder and thereafter to compress the said air; means adapted to cause a reaction in the movement of the said inwardly drawn air and thereby

create a lifting force; and means adapted to permit the escape of the said compressed air at a predetermined pressure point.

3. In an air turbine the combination of the following elements; a housing; a rotatable cylinder mounted therein; means adapted to draw air into the said cylinder and thereafter to compress the same and comprising a series of blades secured to the wall of the said cylinder; a shaft mounted in the said cylinder and adapted to be rotated in either direction; means adapted to cause the reaction in the movement of the said air and comprising a second series of blades mounted on the said shaft; means adapted to rotate the said cylinder and the blades secured thereto; and means adapted to rotate the said shaft and the blades mounted thereon in either direction.

JAMES J. FITZGERALD.
